UNITED STATES PATENT OFFICE.

JOHN M. PRIMM, OF LIMA, OHIO, ASSIGNOR TO THE POWER MANUFACTURING COMPANY, OF LIMA, OHIO, A CORPORATION OF OHIO.

INTERNAL-COMBUSTION ENGINE.

1,150,225.

Specification of Letters Patent. Patented Aug. 17, 1915.

Application filed May 3, 1912. Serial No. 694,811.

To all whom it may concern:

Be it known that I, JOHN M. PRIMM, residing at Lima, in the county of Allen and State of Ohio, a citizen of the United States, 5 have invented or discovered certain new and useful Improvements in Internal-Combustion Engines, of which improvement the following is a specification.

My invention relates to internal combustion engines, and the object thereof is to increase the efficiency of operation and simplicity of construction of such engines.

My invention, although not limited to the use of any specific hydro-carbon as a fuel, 15 is particularly well adapted to the use of liquid petroleum, and its adaptation to such use is illustrated in the accompanying drawings, which form part of my specification.

In these drawings, Figure 1 is an elevation 20 of the preferred form of my engine; Fig. 2 is an enlarged vertical sectional view of the operating cylinder; Fig. 3 is a plan view of the oil pump and water feeding mechanism; and Fig. 4 is a sectional view 25 taken on the line IV—IV, Fig. 3.

In the several figures like numerals are used to designate like parts.

The engine illustrated herein is of the two-cycle type, and in its general construction 30 consists of a closed cylinder 1 within which a trunk piston 2 reciprocates and, through the piston rod 3 and connection rod 4, rotates the shaft 5. The cylinder is divided by the said piston into two communicating chambers 6, 6^a, the chamber 6 being the fuel combustion chamber and 6^a an air compression chamber. Secured to the side of the cylinder 1 there is a pump 7, adapted to inject predetermined quantities of liquid 35 fuel through a tip 8 into the chamber 6 and against an ignition plate 9, carried by the piston 2; the said pump being operated by a rod 10, which is connected to a governor-controlled eccentric 24 carried by the shaft 5. The cylinder 1 is also provided with a suitable water jacket 11, air inlet port 12, 40 exhaust port 13, and auxiliary starting igniter 14.

In the operation of the engine, as thus 45 far described, the forward stroke of the piston 2 creates a partial vacuum at the rear thereof so that air is drawn into the chamber 6^a through the port 12 when the said port becomes uncovered by the piston 2. 50 Also the forward stroke of the piston 2 com-

presses, within the chamber 6, air, previously admitted into the said chamber through the port 15, and oil vapor, pumped therein through the tip 8. This compressed combustible mixture then becomes ignited by 60 the auxiliary igniter, during the starting of the engine, and by the ignition plate 9 after the engine has been running long enough to heat the said plate. In the return or power stroke of the piston, the air taken into the 65 chamber 6^a is compressed, and, following upon the opening of the exhaust port 13, the air inlet port 15 is opened so that compressed air may enter chamber 6, the air being deflected to move horizontally by the 70 abutment 16, and becoming effective both to drive the gases of combustion from the chamber 6 and to furnish oxygen for the next combustible mixture. And in this cycle of operation the pump 7 forces a finely divided spray of oil through the tip 8 into the chamber 6, where the oil becomes vaporized by the heat of the said chamber and the plate 9; and the pump is preferably arranged to act as the piston 2 approaches the 75 forward end of the chamber 6.

In the operation of engines such as are described above water has, in various ways and for various purposes, been admitted into the cylinder and mixed with the combustible 80 mixture. I have found that the efficiency of such engines may be materially increased by water-jacketing only the portion of the cylinder that incloses the combustion chamber, and admitting water to the air-compression chamber after the piston has moved through the greater portion of its forward or charge-compressing stroke, such water becoming vaporized by the uncooled cylinder walls surrounding the air-compression 85 chamber and becoming mixed with the air also let into such chamber, the mixture being thereafter charged into the combustion chamber to form a part of the combustible mixture. The water which I use for this 90 purpose is preferably taken from the water jacket 11 of the forward part of cylinder 1, and injected in predetermined quantities into the chamber 6^a by means of the oil pump 4, which I will now describe.

An oil-receiving chamber 16 is suitably provided with a reciprocating plunger 17, which may be slidably mounted in a collar 18 and held yieldingly in its outward position by a spring 19, bearing against the said 100

collar and against a shoulder 20, secured to the said plunger. This plunger 17 may also be provided with a second shoulder 32, adapted to be engaged by the collar 18 in order to limit the extent of the outward movement of the said plunger. Oil, from a suitable source and under a suitable pressure, may be admitted to the chamber 16 through the opening 21, there being a valve 22 covering the said opening; and the extent of movement of the said valve may be adjusted by a suitable adjusting-screw 23, against the inner end of which the stem of the said valve bears when oil is entering the chamber 16. The oil pump is operated by the rod 10, which may be reciprocated, as described above, by the governor-controlled eccentric 24, the arrangement being such that the transverse movement of the rod 10 is inversely proportional to the rotary speed of the shaft 5. The construction of the governor-controlled eccentric, shown herein, is described and claimed in my Patent No. 1,057,271 and need not here be specifically described.

In order to control the admission of water to the chamber 6^a by means of the above described oil pump, I preferably provide a valve 25, adapted to control the communication between the water supply pipe 26, leading preferably from the water jacket 11, and the interior of the chamber 6^a; and I connect the operating lever 27 of the said valve to the shoulder 20 of the plunger 17 by means of a link 28. The arrangement of this construction is such that, when the plunger 17 is in its outward position, the valve 25 is closed, and that, when the plunger is moved to the left by the rod 10, the said valve will be opened for the time, and according to the extent of the movement of the said plunger. It will readily be seen that the quantity of water-vapor mixed with the air in the chamber 6^a is, for each stroke of the engine, in proportion to the quantity of oil pumped into the chamber 6.

To the end that the operation of the pump may be stopped when desirable, a suitable bell-crank lever having an arm 29 and an abutment 30 may be pivoted in such a position that the abutment 30 may be brought to bear against the shoulder 20 of the plunger 17, and hold the said plunger within the chamber 16. Also the pipe 26 may be provided with a second valve 31, which may be closed when the bell-crank lever 29, 30, is, as is shown in the drawings, made effective to stop the operation of the pump.

In the operation of the engine the reciprocating rod 10 is preferably so timed that its forward pump operating movement will take place as the piston 2 moves forwardly in the cylindrical chamber 6. Oil enters the chamber 16 through the opening 21 as the plunger 17, under the action of the spring

19, is withdrawn from the said chamber. The forward stroke of the plunger 17 is then effective to force the previously admitted oil through the spring-valve 33, pipe 34, and tip 8 into the chamber 6 and against the forwardly moving ignition plate 9. Within the said chamber 6 the sprayed oil becomes vaporized by the heat of the chamber, and mixes with the previously admitted mixture of air and water-vapor; and, when the mixture of oil-vapor, water-vapor and air becomes sufficiently compressed it is ignited, as described above, either by the igniter 14 or the plate 9.

The governor controlled eccentric 24 effects the reciprocation of the rod 10; and of this construction it will be understood that the extent of the reciprocation of the rod diminishes as the speed of the engine increases, with the result that proportionately less oil and less water are admitted to their respective cylinder chambers.

I claim as my invention:

1. In an internal combustion engine, the combination of a cylinder provided with supply and exhaust ports, a piston movable therein and dividing said cylinder into combustion and air-compression chambers, a passageway affording communication between said chambers, means for admitting air into said compression chamber, means for admitting water into said compression chamber in quantities varying according to the speed of reciprocation of said piston and after the piston has traveled through the greater part of its forward or charge-compressing stroke, the water vaporizing and mixing with the air in said compression chamber, and means for charging said mixed air and water vapor into said combustion chamber to form a part of a combustible mixture.

2. In an internal combustion engine, the combination of a cylinder provided with supply and exhaust ports, a piston movable therein and dividing said cylinder into combustion and air-compression chambers, a passageway affording communication between said chambers, a single means effective after said piston has traveled through the greater part of its forward or fuel-compression stroke, for admitting water and fuel into said compression and combustion chambers respectively, and in quantities varying according to the speed of reciprocation of said piston, the water becoming vaporized by the heat of the cylinder walls, means for charging air into said compression chamber to become mixed with the water vapor therein, and means for admitting said mixed air and water vapor into said combustion chamber to form a part of a combustible mixture.

3. In an internal combustion engine, the combination of a cylinder provided with supply and exhaust ports, a piston movable

- therein and dividing said cylinder into combustion and air-compression chambers, a passageway affording communication between said chambers, means for cooling the walls 5 of said cylinder except the portion thereof surrounding said air-compression chamber, means for admitting air into said compression chamber, means for admitting water into the compression chamber in quantities 10 varying inversely with the speed of reciprocation of said piston after said piston has traveled through the greater part of its forward charge-compressing stroke, such water becoming vaporized by the uncooled 15 walls of said cylinder and mixing with said admitted air, and means for charging said mixed air and water vapor into said combustion chamber to form a part of a combustible mixture.
- 20 4. In an internal combustion engine, the combination of a cylinder provided with
- supply and exhaust ports, and a piston movable within said cylinder and dividing it into communicating combustion and air-compressing chambers, a water supply conduit 25 opening into the air-compressing portion of said cylinder, a valve controlling the flow of water through such conduit, a reciprocating oil injection pump adapted to intermittently feed charges of fuel into said combustion 30 chamber, and operative connection between said oil pump and said valve whereby the flow of water through said conduit into said air-compressing chamber is controlled simultaneously with the feeding of the fuel into 35 said combustion chamber.

In testimony whereof I have hereunto set my hand.

JOHN M. PRIMM.
